UNITED STATES PATENT OFFICE.

LEE J. FORET, OF LOCKPORT, LOUISIANA.

APPARATUS FOR BLEACHING LIQUIDS.

1,208,534.

Specification of Letters Patent. Patented Dec. 12, 1916.

Application filed January 22, 1916. Serial No. 73,659.

To all whom it may concern:

Be it known that I, LEE J. FORET, a citizen of the United States, residing at Lockport, in the parish of Lafourche and State of Louisiana, have invented certain new and useful Improvements in Apparatus for Bleaching Liquids; and I do hereby declare the following to be a full, clear, and exact description of the invention, such as will enable others skilled in the art to which it applies to make and use the same.

My invention relates to improvements in apparatus for bleaching liquids, and is more especially intended to provide suitable apparatus in which the raw juice from sugar cane or sugar beets may be treated with sulfur dioxid (SO_2), or other gases.

My invention is especially intended to provide an improved device known as a "sulfur box," in which the raw cane juice is treated with sulfur dioxid, and in which the juice is separated into finely divided sheets or sprays, and is thoroughly and efficiently exposed to the action of the bleaching gas.

My invention is intended to provide a simple apparatus which is not likely to get out of order, and in which the parts exposed to the action of the juice may be readily taken apart or put together for convenience of assembly, or for purposes of cleansing the same.

My invention will be understood by reference to the accompanying drawings, in which the same parts are indicated by similar reference symbols throughout the several views.

Figure 1 shows a sectional elevation of the complete sulfur box with the pipes leading thereto and therefrom; Fig. 2 is a plan view of the device shown in Fig. 1; Fig. 3 shows a section along the line 3—3 of Fig. 1, and looking down; Fig. 4 shows a section along the line 4—4 of Fig. 1, and looking down; Fig. 5 shows the ball bearing for the upper end of the spindle; and Fig. 6 shows the ball bearing for the lower part of the spindle on which the rotating disks are mounted.

The sulfur box is made of a casing 1, preferably composed of a series of cast sections flanged at each end, as at 2, and connected together by bolts or rivets in any convenient way. On the interior of this casing a series of annular ribs 3 are provided, which may be cast integral with the casing, or attached thereto, as preferred.

The lower end of the casing is closed by a bottom casting 4, preferably funnel-shaped, as shown, and this casting is preferably provided with flanged webs 5 to serve as a support for the superposed structure. Mounted on the interior of the bottom casting 4 is a spider 6, which supports the ball bearing 7 for the lower end of the spindle 8. The upper end of this spindle passes through the stuffing box 10 in the head 9, and this head carries a spider 11 supporting the ball bearing 12 for the upper end of the spindle; above which ball bearing suitable means for rotating the spindle are provided. I have shown in Fig. 1 a pulley 13, indicated in dotted lines, but any other suitable means for rotating the spindle 8 may be adopted if desired. Secured to the spindle 8 are a series of disks 14, each provided with collars 15 adapted to slip over the spindle 8, and each collar is provided with a set screw 16, by means of which the disk is secured fast to the spindle 8.

Mounted on the annular ribs 3 on the interior of the casing are a series of annular shelves 17, each preferably made in two parts, as shown in Figs. 3 and 4, for convenience of assembly. These shelves 17 preferably project in toward the spindle beyond the outer edges of the disk 14 above the same, as shown in Figs. 1 and 3.

The raw juice to be treated is fed in through the main 18 controlled by the valve 19, and is carried off through the bottom pipe 20, controlled by the valve 21. The sulfur dioxid, or other gas or gases, is fed into the casing near the bottom by the pipe 22, controlled by the valve 23, and escapes through the pipe 24 controlled by the valve 25. The sulfur stove, or other source of supply of gas, (not shown) is connected to the pipe 22.

The operation of the device is as follows:—The raw juice coming through the main 18 falls on the upper disk 14 and upon the upper shelf 17, and thence passes through the opening in this shelf 17 and falls on the disk 14 below, and, falling over the edge of this disk, it drops on the second shelf 17 from the top, whence it is delivered to the third disk, and so on. The spindle 8 being continuously in operation, the juice is thrown from each disk in a thin umbrella-like sheet, with more or less spray, and falling on the shelf below it is deflected toward the center of the next lower disk,

where it is again thrown outward. The disks being in rapid rotation cause the juice to spread out in thin film-like sheets, and all parts of the juice are particularly exposed 5 to the gases which are moving in the opposite direction to the liquid. By having the disks 14 of greater diameter than, or overlapping, the openings in the center of the annular shelves 17, the juice is caused to follow 10 a zig-zag course, which course is modified by the centrifugal force imparted to the liquid by the rotary disk from which it falls. Thus, a series of cylindrical, or umbrella-like curtains of spray, or thin layers of juice, 15 are formed, through which the gases pass, and by which the bleaching elements are absorbed.

By having the shelves 17 made in halves and loosely mounted on the annular ribs, as shown, they may be readily removed from the apparatus when the disk above is removed, and these disks may be readily taken off from or applied to the central spindle, when desired, by adjusting the set screws 16. 25 Since the weight of the juice on the several disks is considerable, ball bearings are provided to reduce friction, the upper one of which is especially effective in sustaining the weight on the spindle 8, and the parts 30 carried thereby, and is not exposed to the corrosive effect of the bleaching agent, or the juice.

Having thus described my invention what I claim and desire to secure by Letters Patent of the United States is:—

1. An apparatus for bleaching cane and beet juice, comprising a vertically-disposed cylindrical casing provided with a series of

annular ribs on the interior thereof, and a series of annular shelves loosely mounted 40 on said ribs, the said shelves being each formed of two semi-circular segments, a vertical spindle projecting down through the center of said casing and provided with a series of circular disks secured thereto, with 45 means for supplying the liquid to be treated to the upper part of said casing and for conveying the treated liquid from the lower part of said casing, and means for supplying a gaseous reagent to the lower part of 50 said casing and for carrying off the waste gases from the upper part of said casing, substantially as described.

2. An apparatus for bleaching cane and beet juice comprising a vertically-disposed 55 cylindrical casing provided with a series of annular ribs on the interior thereof, and a series of annular shelves mounted loosely on said ribs, the said shelves being each formed of two semi-circular segments, a vertical spindle projecting down through the center of said casing and provided with a series of circular disks secured to said spindle, said disks overlapping the inner edges 60 of the annular shelves, means for rotating said spindle, means for supplying the liquid to be treated to the upper part of said casing and for conveying the treated liquid from the lower part of said casing, and means for supplying a gaseous reagent to the lower 65 part of said casing and for carrying off the waste gases from the upper part of said casing, substantially as described.

In testimony whereof, I affix my signature.

LEE J. FORET.
